UNITED STATES PATENT OFFICE.

FRANK XAVER HERFORT, OF BERGENFIELD, NEW JERSEY.

DESIGN FOR A WEATHER VANE.

Application filed January 21, 1922. Serial No. 302. Term of patent 3½ years.

To all whom it may concern:

Be it known that I, FRANK XAVER HERFORT, a citizen of the United States, residing at Bergenfield, in the county of Bergen and State of New Jersey, have invented a new, original, and ornamental Design for a Weather Vane, of which the following is a specification, reference being had to the

accompanying drawing forming a part thereof.

The figure is a side elevation of my new design.

I claim:

The new and ornamental design for a weather vane, as shown.

FRANK XAVER HERFORT.
